United States Patent Office

Des. 211,303
Patented June 4, 1968

211,303

HANDBAG CLOSURE CLASP

Etienne Aigner, 40 5th Ave., New York, N.Y. 10003

Filed Sept. 27, 1967, Ser. No. 8,760

Term of patent 14 years

(Cl. D87—2)

FIG. 1

FIG. 2

FIG. 3

FIG. 1 is a front elevational view of a handbag closure clasp showing my new design;

FIG. 2 is a rear elevational view thereof; and

FIG. 3 is a side elevational view thereof.

I claim:

The ornamental design for a handbag closure clasp, substantially as shown.
